chine Company, Chicago, Ill., a corporation of
Illinois

Application July 30, 1940, Serial No. 348,372

14 Claims. (Cl. 112—269)

This invention relates to fabric joining seams, and has reference more especially to flat seams in which parallel rows of fabric penetrating stitches extend along the edge margins of juxtaposed fabric portions united by the seams.

This invention is concerned with the provision of a knitted multi-wale covering web for seams of the kind referred to, whereof individual loops are interlocked with individual fabric penetrating loops of the several uniting stitch rows; and also has to do with the provision of a simple method which makes possible the continuous formation of the covering web concurrently with the seam proper.

In the drawings,

Figs. 1 and 2 are fragmentary views respectively showing the face and back of a compound, covered, flat seam conveniently embodying the invention.

Fig. 3 is a view partly in side elevation and partly in vertical section of a combined sewing and knitting machine suitable for carrying out the method by which the seam is formed.

Fig. 4 is a horizontal detail sectional view taken as indicated by the angled arrows IV—IV in Fig. 3.

Fig. 5 is a detail view in cross section taken as indicated by the angled arrows V—V in Fig. 4.

Fig. 6 is a perspective view of one of the elements of the knitting mechanism of the machine.

Figs. 7, 8, 9, 10, 11, 12 and 13 are fragmentary views generally like Fig. 3 showing successive steps in the cycle of stitch formation in accordance with the invention.

Figs. 14 and 15 are fragmentary views corresponding to Fig. 4 with the parts positioned as shown respectively in Figs. 7 and 13.

As exemplified in Figs. 1 and 2, the improved seam comprises four laterally-spaced longitudinal rows or lines 16, 17, 18 and 19 of serially-connected stitch loops formed from separate needle threads T, T', T² and T³. The stitch loops of the lines 16, 17 and 18, 19 respectively penetrate the margins of juxtaposed edge-abutted fabric portions F and F' joined by the seam. At the back of the seam a single thread T⁴ connects the stitch loops of the lines 16, 17, 18 and 19, the loops constituting successive cross rows being designated 16a, 17a, 18a, 19a and 16b, 17b, 18b, 19b respectively. As shown, the thread T⁴ extends transversely through the stitch loops of the successive cross rows, and also zig-zags back and forth between them, thereby forming a concatenation by which said loops are mutually interlocked at the back of the fabric. In so far

as it is described above, the seam is identical with that featured in U. S. Patent No. 1,214,563, granted to Chester McNeil on February 6, 1917. As herein instanced, the improved seam is covered at the front face thereof by a weft-knitted selvage-edged knitted web of corresponding width formed from another thread T⁵. Successive courses of the covering web are designated by the numerals 21 and 22, and the needle loops of these courses by the characters 21a, 21b, 21c and 22a, 22b, 22c. In the course 21, the sinker wale loops 21d, 21e and 21f respectively embrace the fabric penetrating loops 16a, 17a and 18a; while in the course 22, the sinker wale loops 22d, 22e, and 22f embrace the fabric penetrating loops 17b, 18b and 19b; the fabric penetrating loops 16b and 19a of the outer lines 16 and 19 being skipped. As will be presently seen, the seam is formed incident to concurrent advance of the two fabric portions F and F' in the direction indicated by the arrows in Figs. 1 and 2.

The seam is producible commercially by a method which can be conveniently carried out on the combined sewing and knitting machine illustrated in part in Figs. 3 and 4. As shown, this machine has a work support 25, a gang of four transversely arranged sewing needles 26, 27, 28 and 29 which carry the threads T, T', T² and T³ and which are fixed in a cross head 30 at the lower end of a vertical axis needle bar 31 guided for endwise or axial reciprocation in a head 32 on the frame (not illustrated) of the machine. The sewing needles 26—29 move up and down through individual openings 33 in the work support 25, and cooperate beneath said work support with a looper 35 which manipulates the thread T⁴. The fabric being seamed is intermittently progressed on the work support 25 in the direction of the arrow in Fig. 3 by a four-motion feed dog which has the toothed portions 36 and 37 operating upwardly through slots 38, 39 in said support, and which are opposed from above by a presser foot 40 having individual apertures 41 for passage of the needles. At the top, the presser foot 40 has a short shank or boss 42 whereby it is secured, with the aid of set screws 43, to the lower end of a vertical presser bar 45, which, like the needle bar 31, is confined to axial movement in the head 32. Through suitable actuating mechanism (not shown) such as is well known in the art, the needles 36—29, the looper 35 and the feed dog 36—37 are operated in properly timed relation to determine formation of the sewed portion of the seam, i. e., the seam proper, hereinbefore described.

In order that the knitted face covering of the seam may be formed concurrently with the seam proper, the machine has been modified in the manner about to be set forth. As shown in the drawings, the upright rear portion 50 of the presser foot 40 has a longitudinal hollow with vertically spaced horizontal grooves 51 and 52 in the inner faces of its side walls 53, 54. Slidably guided in the upper pair of grooves 51 is a plate 55 with a central aperture engaged by an up-standing stud 56 on a swivel cross head 57 whereof the ends are engaged in the lower pair of grooves 52. In the interval between the swivel cross head 57 and the slide 55, a spacing collar 58 surrounds the stud 56; and a cap screw 59 engaging axially into the top of said stud serves as a means for holding these parts assembled. The swivel head 57 is recessed crosswise as at 60 to engage the butts 61 of three horizontally arranged latched knitting needles 62, 63 and 64 which are slidably guided in parallel grooves formed in a lug 65 upstanding from the bottom of the presser foot 40. As shown in Fig. 4, the knitting needles 62, 63 and 64 are arranged to pass back and forth centrally of the intervals between the four sewing needles 26, 27, 28 and 29, and are adapted to be actuated by reciprocation of the slide 55 through a link 66 from a moving part (not illustrated) of the sewing machine. The swivel head 57 is provided with a rearwardly extending arm 67 carrying a stud 68 whereof the upper and lower ends engage slots 69 in the contiguous bifurcated end of an actuating member 70. For a purpose later on explained, this actuating member 70 swings the swivel head 57 about its pivotal connection with the slide 55 through motion induced by a moving part (not illustrated) of the machine. The office of feeding the knitting thread T^5 is relegated to the carrier in the form of an apertured finger 71 at the lower end of a vertical supporting stem 72. As shown, the stem 72 extends downwardly from a collar 73 at the lower end of an oscillating sleeve 74 surrounding the needle bar 31 within the needle head 32.

The cycle of stitch formation is as follows: In Figs. 7 and 14, the knitting needles 62, 63 and 64 are advanced substantially to the full extent in the intervals between the sewing needles 26-29 which are in their lowered fabric-penetrating positions; while the feed 71 is remote from the observer in Fig. 7 after having been swung to one side (upward in Fig. 14) to lay the knitting yarn T^5 crosswise of the fronts of said sewing needles at a level where it can be taken by the knitting needles. It is also to be noted in connection with Figs. 7 and 14 that the hook ends of the knitting needles 62-64 are arranged at a slope, which arrangement was brought about by movement of the swivel head 57 anti-clockwise through an angle of forty-five degrees from the normal position in which it is shown in Fig. 4. With the foregoing accomplished, the knitting needles 62-64 are bodily moved in the direction of fabric feeding from the position of Figs. 7 and 14, through the positions shown in Figs. 8 and 9, to the position shown in Fig. 10, with resultant drawing of the loops 21a, 21b and 21c of a course 21 of the knitted covering around the sewing needles 27, 28, 29. By reason of the sloped arrangement of hook ends of the knitting needles 62-64, the loops 21d, 21e and 21f are successively drawn from the supply of the thread T^5 with consequent avoidance of undue strain upon said thread. After the knitting needles 62-64 have received their full retractive movement, the

swivel head 57 is swung back to its normal or true crosswise position to transversely align said needles for equal apportionment of the knitting thread T^5 between the three loops 21d, 21e and 21f. During the retractive stroke of the knitting needles 62-64 just explained, the needle latches are closed by the previously formed loops 21a, 21b and 21c which are restrained by the rear edges of the openings 41 in the presser foot 40, and, as a consequence, cast off said needles as shown in Fig. 10. The last described action occurs shortly before the sewing needles 26-29 are elevated to the full extent shown in Fig. 10, and just before the feed dogs 36 and 37 begin their active strokes to advance the fabric F with incidental pulling of the newly shed loops 21a, 21b and 21c, as shown in Fig. 10, downward through the openings 41 in the presser foot 40. In Fig. 11, the sewing needles 26-29 are descending while the knitting needles 62-64 are being advanced to thread taking position. In Fig. 12, the knitting thread carrier 71 is being moved toward the observer to lay the thread T^5 across the knitting needles 62-64 forwardly of the sewing needles 26-29 while the latter continue in their descent and penetrate the fabric F. In Fig. 12, the sewing needles 26-29 are at the limit of their downward movement and the knitting needles 62-64 at the limit of their outward movement, the swivel head 57 having been swung clockwise from the normal position in which it is shown in Fig. 4, whereby the hook ends of the knitting needles predetermine the reversely sloped relation of the needle hooks shown in Fig. 15. With the immediately foregoing accomplished, the knitting needles 62-64 are retracted to form the loops 22a, 22b and 22c of a course 22 of the knitted covering from the thread T^5 , while the loops 21a, 21b and 21c of the previously formed course 21 are cast off. Repetitions of the above cycle, incident to which the knitting thread carrier 71 is swung alternatively crosswise of the seam from one side to the other, will obviously result in the formation, concurrently with the sewing, of the weft knit covering at the face of the fabric F with the selavage loops 21d, 22d respectively at opposite ends of its successive courses 21, 22.

The means for moving the parts 66 and 67 in properly timed relation with the sewing instrumentalities of the machine to carry out the knitting cycle as above explained may be of any approved design and has been omitted since the present application is concerned only with the seam and the method of its formation.

As an alternative, the covering may be separately formed as a tape and its feeding so controlled in an ordinary multiple needle sewing machine in such manner that the sewing needles are caused to penetrate individual loops in successive courses of the tape, with attainment of exactly the same result in the completed seam.

It is to be understood that the invention is not necessarily limited to compound seams such as herein specifically described where the several lines of fabric penetrating stitches are transversely connected at the back of the fabric, since, by suitable modifications within the scope of the appended claims, it may be embodied in compound seams whereof the stitch lines are entirely independent of one another.

The improved seam is particularly advantageous in connection with articles of wearing apparel such as sweaters, vests and bathing suits made from knitted materials.

Having thus described the invention, what is claimed is:

1. The method of producing a cover seam, which comprises forming parallel rows of fabric-penetrating stitches; and concurrently forming a knitted covering with loops which are arranged in crosswise-connected wales extending in the direction of the stitch rows and causing individual loops of such wales to interlock with individual fabric-penetrating stitches of said rows.

2. The method of producing a cover seam, which comprises forming parallel rows of fabric penetrating stitches and mutually interlocking them at the back of the seam by a concatenation formed from a separate thread; and concurrently forming a knitted covering with loops which are arranged in cross-wise connected loop wales extending in the direction of the stitch rows and causing individual loops of such wales to interlock with individual fabric-penetrating stitches of said rows.

3. The method of producing a cover seam, which comprises forming parallel rows of fabric penetrating stitches and mutually interlocking them at the back of the seam by a concatenation formed from a separate thread; and concurrently forming a plain weft knit covering from another thread with loops which are arranged in wales extending in the direction of the stitch rows and causing individual loops of such covering to interlock with individual stitches of said rows.

4. The method of producing a cover seam by repetitions of a cycle which comprises forming parallel rows of sewing stitches with a group of transversely spaced needles from as many different sewing yarns and locking such stitches at the back of the fabric; and, while the needles are in the fabric, successively forming around them a course of knitted fabric loops from a separate knitting thread with the component loops of such course interlocking with the individual sewing stitches of the several rows at the face of the fabric.

5. A fabric-joining seam comprising a plurality of spaced rows of fabric-penetrating stitches which are interlocked at one face of the fabric and which, at the opposite face of the fabric, are interconnected by a cover thread which is secured to the face of the fabric by the stitch threads and which is laid across the seam in opposite directions at successive stitches, said cover thread being formed, at and between the parallel rows of stitches, into loops which are interengaged with adjacent similar loops of the cover thread longitudinally of the seam.

6. A fabric-joining seam comprising parallel

rows of fabric-penetrating stitches and a knitted covering at one face of the fabric with its rib wales extending lengthwise between the fabric-penetrating stitch rows and composed of loops which correspond in number to the stitches of the respective rows; and with thread segments crosswise connecting the loops of adjacent wales interlocked with individual stitches of said stitch rows.

10 7. A fabric-joining seam according to claim 6, in which the fabric-penetrating stitches of the respective rows are crosswise connected at the opposite face of the fabric.

15 8. A fabric-joining seam according to claim 6, in which the fabric-penetrating stitches of the respective rows are formed from individual threads.

20 9. A fabric-joining seam according to claim 6, in which the fabric-penetrating stitch rows are formed from individual threads; and in which the stitches of said rows are crosswise connected at the opposite face of the fabric by another thread.

25 10. A fabric-joining seam comprising parallel rows of fabric-penetrating stitches; and a weft-knitted covering at one face of the fabric with its rib wales extending lengthwise between the fabric-penetrating stitch rows and composed of loops which correspond in number to the stitches of the respective rows; and with the connecting loops of its intervening wales interlocked with individual stitches of said rows.

30 11. A fabric-joining seam comprising parallel rows of fabric-penetrating stitches; and a weft-knitted selvage-edged covering at one face of the fabric with its rib wales extending lengthwise between the fabric-penetrating stitch rows and composed of loops which correspond in number to the stitches of the respective rows, and with the connecting loops of its intervening wales interlocked with individual stitches of said rows.

35 12. A fabric-joining seam according to claim 11, in which the fabric-penetrating stitches of the several rows are crosswise connected at the opposite face of the fabric.

40 13. A fabric-joining seam according to claim 11, in which the fabric-penetrating stitch rows are formed from separate threads.

45 14. A fabric-joining seam according to claim 11, in which the fabric-penetrating stitch rows are formed from individual threads; and in which the stitches of said rows are crosswise connected at the opposite face of the fabric by another thread.

50 JOHN F. CAHILL,
Administrator de bonis non of the Estate of
Albert S. Riviere, Deceased.
